VALVE

Charles F. Johnson, Houston, Tex., assignor to
Reed Roller Bit Company, Houston, Tex., a cor-
poration of Texas

Application August 16, 1941, Serial No. 407,175

4 Claims. (Cl. 251—102)

This invention relates to valves, and has for its general object the provision of a valve in which the destructive action of the fluid controlled by the valve on the valve closure elements will be reduced to a minimum.

It has been proposed in previous valve constructions to provide valves in which the closure members are lifted away from their seats in order that they might be moved laterally with respect to their seats with a reduced frictional resistance. In such arrangements in the past, however, the lifting of the closure member from its seat has depended upon the frictional resistance to movement offered by the closure member. That is, when an opening movement was exerted on the valve closure member, if there was a high frictional resistance to movement of such member, then the opening effort would be expended partially in lifting such member from its seat so as to reduce the frictional resistance. When the member is urged from its seat, however, with a sufficient force to reduce its frictional resistance below a certain point, it will begin to slide sidewise with respect to its seat without actually being lifted off its seat.

It is highly desirable, however, especially with structures in which the seats are all formed of relatively soft material, that the closure members be lifted completely away from their seats before being moved laterally to any substantial degree, so that the material of the seat will not be torn or injured by the lateral sliding of the closure member thereon.

It is, therefore, an object of this invention to provide a valve structure in which the closure members will first be lifted directly away from their seats before being moved laterally with respect thereto in opening the valve.

It is a further object of this invention to provide a structure of the type referred to in which the valve closure members will be held out of frictional contact with their seats until they are in position directly opposite their seats, whereupon they may be allowed to move directly toward their seats instead of with a sliding movement over their seats.

Another object of this invention is to provide a valve of the type referred to in which the segments may be held against seating upon any portion of the valve structure during any desired portion of the opening and closing movement thereof.

Another object of this invention is to provide a valve structure in which the corrosive effects

of the liquid controlled by the valve will be minimized.

Other objects and advantages of this invention will become apparent from the following description taken in connection with the accompanying drawings, wherein are set forth by way of example and illustration certain embodiments of this invention.

In the drawings:

10 Fig. 1 shows a vertical transverse cross section through a valve constructed in accordance with this invention, the carrier in this instance being illustrated in elevation and shown in closed position;

15 Fig. 2 is a view of the same valve shown partly in horizontal longitudinal cross section and partly in top plan with the valve cover plate removed;

20 Fig. 3 is a view similar to Fig. 1 but illustrating only the housing and liner of the valve without the valve carrier, closure members or cover plate in position;

25 Fig. 4 is a view similar to the lower portion of Fig. 2 but illustrating the valve in open position;

Fig. 5 is a view similar to the upper portion of Fig. 2 but illustrating the valve in a semi-closed position, but during the opening movement thereof;

30 Fig. 6 is a view similar to Fig. 5 but showing the valve in semi-closed position during the closing movement thereof;

Fig. 7 is a view similar to Figs. 5 and 6 but showing a slightly modified form of valve in 35 fully open position.

Referring to Fig. 1, the numeral 1 indicates the valve housing. This housing provides a cylindrical valve chamber closed at its lower end as shown at 2 by an integral closure and at its 40 upper end as shown at 3 by a separate cover plate. This cover plate may be held in place by studs and nuts 4 or by any other suitable means. Leading from the cylindrical valve chamber in opposite directions are ports 5 and 6 45 either of which may serve as the inlet and the other as the outlet for the valve.

Carried within the valve body and forming a liner therefor is a cylindrical member 7 open at both ends and having a laterally extending flange 8 at its upper end adapted to seat upon a gasket 9 carried on a shoulder 10 adjacent the upper end of the cylindrical chamber. This liner 7 has cut out portions or segments providing openings which are much larger than and surrounding the inlet and outlet ports 5 and 6.

Carried in these openings are segmental seating members 11 formed of rubber or the like molded over a suitable core or frame 12 of relatively strong metal or other material for supporting the rubber seat and holding it in shape.

A valve carrier 13 is rotatably mounted within the interior of the liner 7 by means of a pintle 14 adjacent its lower end, said pintle engaging the socket 15 in the lower end of the valve housing. The upper end of the carrier is rotatably supported by means of the stem 16, which passes through an opening in the cover plate 3. Leakage along this stem is prevented by means of packing 17 in the stuffing box formed in the cover plate, this packing being compressed by means of a gland 18 held down by studs and nuts 19 or the like.

The carrier itself is of a size such that it does not contact either the liner 7 or the seats 11, which are carried thereby. This valve carrier has an opening therethrough in one direction so that when in one position it will provide a passage directly through the valve chamber from one port 5 to the other port 6 or vice versa. Also carried upon this carrier are two closure segments 20 and 21 respectively, which are adapted to seat against the seat inserts 11 when the carrier is moved to closed position. These closure members 20 and 21 each have on opposite ends thereof lugs 22 providing inclined faces 23 adapted to be engaged by hooks 24 on the carrier. Thus, when the carrier is rotated as in moving from closed to open position, the action of the hooks 24 upon the inclined surfaces of the lugs 22 will tend to draw the segments away from their seats and toward the center of rotation of the carrier.

In accordance with this invention, each of the lugs 22 is also provided with a raised portion 25 on its outer surface, which portion is adapted to slide along the adjacent portion of the liner 7. The liner 7 is provided throughout portions of its circumference adjacent its opposite ends of the liner with raised portions 26, which act as rails upon which the projections 25 ride. These rails terminate, as illustrated, at the points occupied by the projections 25 when the valve is in fully closed position, so that they will not prevent the valve closure elements 20 and 21 from seating against the seat 11 when the valve is in closed position. However, when opening movement of the valve is begun, the ends of the rails 26 will prevent rotative movement of the closure members until the closure members have moved inwardly toward the center of rotation of the carrier a sufficient amount to permit the projections 25 to ride up on the rails 26. The segments 20 and 21 will then be held out of frictional engagement with the inner wall of the liner 7 as long as the projections 25 are riding on the rails 26, and the extent of this engagement will, of course, be determined by the extent of the rails 26. In the forms shown in Figs. 1 to 6 inclusive, the rails 26 are of such an extent as to hold the segments out of frictional contact with the inner surface of the liner at all times except when the valve is in fully closed position. The form shown in Fig. 7 is identical to that just described except for the fact that the rails 26' in this form are caused to terminate at 27 in a position such that when the valve is fully opened the projections 25 will not be in contact with the rails 26' and the valve segments may, therefore, seat against the inner wall of the housing when the valve is fully opened.

In operation, the valve closure members will contact their seats and prevent the flow of fluid when the valve is in closed position exactly the same as in the structures of the prior art. However, when the opening movement of the valve is begun, the first movement of the valve segments with respect to their seats will be a movement which will actually move them out of frictional contact with their seats. There will not be merely a lifting effort exerted upon the valve segments so as to reduce friction between them and their seats, but the valve segments will actually be lifted away from their seats before any rotative movement of the closure members can take place. When the valve closure members are thus moved away from their seats until the projections 25 can ride up on the rails 26, and only after this has taken place, there may be a rotative movement of the valve segments to open position, which position is illustrated in Fig. 4 of the drawings. It will be seen by reference to Fig. 5 that during the opening movement of the valve the segments will be held out of contact with the inner surface of the liner 7 during this entire movement, and that when the valve is open the segments will still be held out of contact with the inner wall of the liner as shown in Fig. 4. Being so held out of contact with the inner wall of the liner while the valve is in open position, there will be no tendency for the formation of precipitates from the fluid being handled to cause the valve segments to stick in open position and there will be no hindrance to the closing movement of the valve even after it has been open for a long period of time. This may be found highly desirable for certain types of surfaces depending upon the nature of the fluid being handled and other factors such as pressure, temperature and the like.

In other cases, it may be found desirable that the segments seat against the inner surface of the liner when in open position and this can be accomplished as illustrated in Fig. 7 by causing the termination of the rails at an appropriate point so that when the valve is fully open the projections 25 will not be on the rail.

On closing movement of the valve, it will likewise be held out of frictional contact with the liner by the rails 26 or 26' as the case may be. This is clearly illustrated in Fig. 6 of the drawings. By this means any frictional resistance to the closing movement of the valve due to the pressure of the fluid being handled may likewise be eliminated. Furthermore, it will be noted that no valve closure member can be slid sidewise onto its seat any more than it can be slid sidewise from its seat. Instead, each closure member will be held out of frictional contact with the liner and with its seat until it is in position directly opposite the opening through its seat. Thereupon, it will be caused to move in a substantially radial direction toward its seat with very little rotative movement as it seats.

It will be appreciated that while this invention has been illustrated in connection with a valve employing a liner for holding the valve seat elements, a different construction might be employed in which no liner is used and in which the valve seat elements are held by appropriate means carried by the valve housing. It will further be apparent that the rails 26 or 26' in such instances could be formed directly on the valve housing or on some other appropriate part, as desired.

It will further be appreciated that while this invention is particularly advantageous when used

in connection with a valve employing soft or resilient valve seats, it is not limited to use with such valve but may be used with valves not employing such seats.

It will be appreciated that by the foregoing invention, there has been provided a valve in which the valve closure members may be moved laterally to and from seating position but will be held out of frictional contact with the walls of the valve chamber or its liner at all times when it is not specifically desired that they come in contact with such chamber or liner. It is further noted that by means of this invention the closure members of a valve may be held out of engagement with the valve body and the valve seats at all points desired, both in the opening and closing movement of the valve, and while the valve is fully opened, and may be caused to seat at such points as may be desired.

It will further be appreciated that by this invention is provided a means whereby a valve closure member may be positively caused to move first directly away from the seat before being moved in a lateral direction in the opening of the valve, and that in the closing movement of the valve it will be held away from its seat until it is directly opposite its seat when it will be moved directly toward its seat.

Having described my invention, I claim:

1. A valve comprising a valve body having a cylindrical chamber therein and ports communicating with said chamber, a carrier rotatably mounted in said chamber co-axially thereof, segmental closure members positioned in said chamber for circumferential movement to and from positions to close said ports and for radial movement away from the wall of said chamber, cooperating means on the closure members and carrier for retracting the closure members and displacing the same, rail-like elements extending circumferentially about portions of said chamber adjacent the ends thereof, and means carried by the closure members adjacent the ends thereof and adapted to engage the ends of said rail-like elements when the closure members are in port closing position to prevent displacement of said closure members by the carrier until said members are retracted and to ride on said rail-like elements during displacement of said members from port closing position.

2. A valve comprising a valve body having a cylindrical chamber therein and ports communicating with said chamber, a carrier rotatably mounted in said chamber co-axially thereof, segmental closure members positioned in said chamber for circumferential movement to and from positions to close said ports and for radial movement away from the wall of said chamber, cooperating means on the closure members and carrier for retracting the closure members and displacing the same, rail-like elements extending circumferentially about portions of said chamber adjacent the ends thereof, and means carried by the closure members and adapted to

engage the ends of said rail-like elements when the closure members are in port closing position to prevent displacement of said closure members by the carrier until said members are retracted

5 and to ride on said rail-like elements during displacement of said members from port closing position, said rail-like elements merging into the chamber wall adjacent the port opening position of the closure members to enable said members 10 to again seat against their seats and to retract said members as they move from port opening to port closing position.

3. A valve comprising a valve body having a cylindrical chamber therein and ports communicating with said chamber, a carrier rotatably mounted in said chamber co-axially thereof, segmental closure members positioned in said chamber for circumferential movement to and from positions to close said ports and for radial 20 movement away from the wall of said chamber, resilient seating means on the wall of the chamber, cooperating means on the closure members and carrier for retracting the closure members and displacing the same, rail-like elements 25 extending circumferentially about portions of said chamber adjacent the ends thereof, and means carried by the closure members adjacent the ends thereof and adapted to engage the ends of said rail-like elements when the 30 closure members are in port closing position to prevent displacement of said closure members by the carrier until said members are retracted and to ride on said rail-like elements during displacement of said members from port closing 35 position.

4. A valve comprising a valve body having a cylindrical chamber therein and ports communicating with said chamber, a carrier rotatably mounted in said chamber co-axially thereof, segmental closure members positioned in said chamber for circumferential movement to and from positions to close said ports and for radial movement away from the wall of said chamber, resilient seating means on the wall of said chamber, cooperating means on the closure members and carrier for retracting the closure members and displacing the same, rail-like elements 45 extending circumferentially about portions of said chamber adjacent the ends thereof, and means carried by the closure members and adapted to engage the ends of said rail-like elements when the closure members are in port closing position to prevent displacement of said closure members by the carrier until said members are retracted 50 and to ride on said rail-like elements during displacement of said members from port closing position, said rail-like elements merging into the chamber wall adjacent the port opening position of the closure members to enable said members 55 to again seat against their seats and to retract said members as they move from port opening to port closing position.

CHARLES F. JOHNSON.
